UNITED STATES PATENT OFFICE.

THOMAS L. TALIAFERRO, OF CHICAGO, ILLINOIS.

METHOD OF FORMING LINERS FOR METAL CAPS AND ARTICLE PRODUCED THEREBY.

Application filed September 1, 1922. Serial No. 585,658.

To all whom it may concern:

Be it known that I, THOMAS L. TALIAFERRO, a citizen of the United States, residing at Chicago, in the county of Cook, State of Illinois, have invented certain new and useful Improvements in Methods of Forming Liners for Metal Caps and Article Produced Thereby, of which the following is a description, reference being had to the accompanying drawing and to the figures of reference marked thereon.

My invention relates to liners for the metallic caps for containers of various kinds.

Heretofore such liners have been formed of disks of pulp board and the like, and a separate disk of oiled paper which were assembled in the cap. Another method was to pass pulp board between rolls which applied a coating of glue or sizing thereon made from albumen, casein, dextrine and the like, but these substances carried more or less moisture, so that in drying, the sheet became warped or the liners formed therefrom would become warped and distorted. Then again different runs of pulp board would absorb more glue than others, which caused trouble in sticking. Furthermore, the glue used afforded no water proofing quality to such liners and it was not possible to glue paper oiled on both sides or throughout, to such a sized surface.

My object is to use the usual pulp sheet and the usual oiled paper of commerce in the formation of liner material, and to provide a novel method of uniting such materials. Also, to provide an improved liner as the result of such method.

This I accomplish in the following manner, the drawing showing in—

Figure 1 a plan view of liner;

Fig. 2 section thereof; and

Fig. 3 is a perspective, with one part of the oiled sheet separated.

I first dissolve chicle or equivalent gum in heated paraffin, or equivalent wax, which forms the water-proofing material. With this solution I coat one side of the pulp board by passing the sheet between rolls which deposit the solution on one side only of the sheet. While the solution is still warm, a sheet of oiled paper is laid on the coated surface and united thereto by pressure, preferably by passing the two superposed sheets between pressure rolls. Actual practice has shown that the gum and paraffin coating will afford a surface to which

oiled paper will adhere. In using paraffin or any wax, in combination with any resinous gum, there is the advantage of not only further water-proofing the pulp board, but this coating will not cause the board to warp as is the case where a water glue is employed; and, furthermore, an oiled surface will adhere thereto sufficiently to permit the liners to be cut from such a composite sheet and applied to the metal caps. Paraffin will dissolve most resinous gums. Most oils will dissolve gum and make it sticky or tacky. It is, therefore, preferred not to use an oil with chicle that would not dry out and so leave the mixture sticky. Therefore, a wax is used which, when melted, forms a medium or vehicle in which chicle or other resinous gum will melt and become a part of.

Other waxes and gums may be employed in lieu of those stated provided the solution produced by the union thereof will be waterproof in its nature and form a coating to which an oiled paper will adhere.

The liner shown in the drawings comprises a disk formed of pulp board 1, having a coating 2, such as above described, and an oiled paper disk 3 united to the coated surface 2, as before described, by the gum and wax solution.

The use of liners formed of separate disks and the expense of assembling them in a cap are avoided and the warping, distortion and sticky surface following the use of water glue in uniting two disks to form a liner are also avoided by my method of uniting an oiled sheet to a pulp sheet, as above described.

Having thus described my invention, what I claim as new and desire to secure by Letters Patent, is:

1. The method of forming liner material which consists in coating a sheet of pulp board with a heated solution of a wax and a gum and then applying a sheet of oiled paper to such coated surface, and pressing the two sheets firmly together.

2. The method of forming liner material which consists in coating a sheet of pulp board with a heated solution of a mineral wax and a vegetable gum, and then applying a sheet of oiled paper to such coated surface and pressing the two sheets together.

3. The method of forming liner material which consists in coating a sheet of pulp board with a heated solution of paraffin

mounted in the guideway 27 and is arranged to be detachably fixed to the lathe bed 9 by means consisting, in the present embodiment, of a rod 29 fixed to said member and 5 slidably extending through an apertured stud 30 attached to the bed, a set screw 31 being provided to clamp the rod 29 in the stud 30.

On the table 28 is pivotally mounted a 10 guide member 32 having upwardly projecting parallel walls defining a rectangular channel. The pin 33 that forms the pivot for the guide member 32 is situated midway of the length of said guide member. 15 Bolts 34 and 35 passing through slots 36 and 37 in the member 28 are adapted to clamp the guide member 32 in adjusted angular position. Additional bolt holes 38 laterally spaced in the guide member 32 are adapted 20 to receive the bolts 34 and 35 to extend the range of adjustment of said guide member.

The operative connection between the bearing member 19, 20 and the guide member 32 will now be described. A block or 25 follower 41 is carried along by a pin 39 and slides in the guide member 32. The pin 39 carries an enlargement 42 holding the block in place and enters a depending lug or projection 40 formed integral with the block 19. The carriage 10 has a slot 43 in which the projection 40 is slidably mounted. Said projection bears against the side walls of the slot 43.

In the operation of my device with the 35 set screw 31 tightened, the table 28 and the guide 32 remain stationary. As the carriage 10 travels, the block 41 slides in the guide 32 and forces the pin 39 to move, and with it the block 19, tool support 14 and the cutting tool, thus cutting the desired taper. When it is desired not to use the taper attachment, set screw 31 may 40 be loosened. The slide 28 and guide 32 will then move with the apron 24 and the block 19 will be effectively locked from transverse movement.

While I have described in detail one embodiment of my invention, it should be clearly understood that the description is 50 illustrative only, and that all legitimate modifications and improvements covered by the subjoined claims are properly within the scope of my invention.

I claim as my invention:

1. A lathe having, in combination, a longitudinally slidable carriage, transverse ways on said carriage, a bearing block 55 slideable in said ways, the upper portion of said bearing block being slotted, additional transverse ways on said carriage, a tool support on said additional ways, said tool support having a lug entering the slot in said

bearing block and adapted to engage a feed screw.

2. A lathe having, in combination, a longitudinally slidable tool carriage; a tool support transversely slideable on said carriage; a cross-feed screw extending below said tool support; a depending lug on said tool support engaging said cross-feed screw; 65 a bearing block supporting said cross-feed screw at one end and having an extension underlying said screw, said extension being cut away to provide clearance for said lug. 70

3. A lathe having, in combination, a longitudinally slidable carriage, a transverse groove in said carriage, a transversely slideable bearing block in said groove, a pair of transverse ways on said carriage on opposite sides of said groove, a tool holder slideable on 75 said ways and overlying said block, and an operative connection between said block and said tool holder.

4. A lathe having, in combination, a longitudinally slidable carriage, a transversely 85 slideable tool support on said carriage, a transversely slideable block mounted in said carriage and extending through the same underneath said tool support, means for adjusting the transverse spacing of said bearing block and tool support, and a taper attachment operatively connected to said transversely slideable block.

5. A lathe having, in combination, a longitudinally slidable carriage, a transversely 95 slideable block in said carriage, and a transverse feed screw supported by and housed in said block.

6. A lathe having, in combination, a longitudinally slidable carriage, a transversely 100 slideable block in said carriage, a tool support transversely slideable on said carriage over said block, a transverse feed screw journaled at one end in said block and extending through a groove formed in the upper face of the block, and a lug depending from said tool carriage having threaded engagement with an intermediate portion of said feed screw, the other end of said feed screw being free and unsupported. 105

7. A lathe having, in combination, a longitudinally slidable carriage, a transversely 110 slideable block in said carriage having a U-shaped recess running substantially its full length, a feed screw rotatably mounted in the block and positioned in said recess, a transversely slideable tool support mounted in said carriage and overlying said block, said support having a lug projecting into said recess in threaded engagement with 115 said screw.

In testimony whereof, I have hereunto set my hand.

GUSTAF DAVID SUNDSTRAND.
